AUTOMATICALLY CLOSING CAP FOR
COLLAPSIBLE TUBES OF CREAM

Vincent Lamagna, Rutherford, N. J.

Application August 4, 1949; Serial No. 108,528

4 Claims. (Cl. 222—511)

1

This invention relates to closures for collapsible tubes containing tooth paste or similar material that is squeezed from the tube in small amounts from time to time. The invention relates more particularly to a self-closing cap that is applied to a collapsible tube in place of a regular cap, and it is a feature of the invention that the cap can be opened by pressure from the tooth brush, the closing being automatic when the tooth brush pressure is withdrawn.

It is an object of the invention to provide an improved self-closing cap for collapsible tubes and to provide a construction for such caps that is economical to manufacture and that is particularly efficient and convenient to use.

One feature of the invention relates to a slide which closes an outlet of the cap, and to a construction whereby the slide is supported in a guideway open at both ends, but provided with concealed limit stops for preventing the slide from traveling in the guideway beyond predetermined limits. Another feature of the invention relates to the construction of the cap with automatic, spring-operated means for closing the cap; and to the construction whereby the spring is housed and retained in the cap, a construction of economical cost.

Other objects, features and advantages of the invention will appear or be pointed out as the description proceeds.

In the drawing, forming a part hereof, in which like reference characters indicate corresponding parts in all the views,

Figure 1 is a sectional view through the discharge end of a collapsible tube with a cap embodying this invention.

Figure 2 is a sectional view taken along the line 2—2 through the cap shown in Figure 1.

Figure 3 is a sectional view taken on the line 3—3 of Figure 1.

A cap 10 has a recess 12 at its lower end threaded to receive a neck 13 of a collapsible tube 14. Above the recess 12, there is a passage 16 extending rearwardly and having a flattened discharge opening 17.

The cap 10 is made in two parts comprising a right hand portion 21, and a left hand portion 22 which meet along a plane 24. These two portions of the cap are secured together in any suitable way, as by adhesive or dowel pins 25 or other fastening means.

When the right and left hand portions 21 and 22 are in assembled relation, they form an undercut slot or channel 26 at the upper end of the cap. This undercut slot, which extends on both sides

2

of the discharge opening 17, serves as a guideway for a slide 30.

The slide 30 is made with a cross section to fit the undercut guideway 26 as a running fit, and one end of the slide 30 has an upwardly extending flange 32 for operating the slide. When the slide 30 is in the full line position indicated in Figure 1, it covers and closes the discharge opening 17; and when the slide 30 is shifted into the dotted line position, the discharge opening 17 is uncovered.

The spacing of the operating flange 32 from the discharge opening 17 is so chosen that a tooth brush 35 with its back pressed against the lip flange has its bristles in position to receive tooth paste 37 as it is squeezed from the discharge opening 17.

The slide 30 can be operated by hand, but the provision of the flange 32, extending from the slide 30 far enough to permit the slide to be operated by the tooth brush has the advantage of permitting the user to hold the tooth brush in one hand and squeeze the tube of tooth paste with the other. The tooth brush is held on a slight slope that brings the upper ends of the bristles, on one side of the brush, adjacent to the top surface of the slide so that movement of the brush and the slide to open the passage leaves the upper ends of the bristles in position to receive tooth paste from the passage 16. The flange 32 extends above the top surface of the slide far enough to prevent the sloping tooth brush from jumping over the flange when pressed against the flange to move the slide into position to uncover the discharge opening.

It would not be convenient to hold the slide 30 open with the same hand as used to squeeze the tooth paste, nor would it be convenient to hold the slide 30 open with the same hand in which the tooth brush is gripped. The feature by which the brush can be used to keep the slide open, therefore, has the advantage of making possible the use of an automatically closing cover which does not increase the effort required to squeeze the tooth paste from the tube. Many self-closing caps of the prior art have used the pressure of the paste to open the cap, but it is evident with such caps the force required to squeeze the paste from the tube is increased, and greatly increased when the paste is stiff and a strong spring pressure is provided to close the cap against the resistance of the stiff paste.

The slide 30 is held in closed position, and restored to closed position after each operation, by a spring 40 housed in a socket between the

right and left hand portions of the cap. This spring 40 is held in place in the illustrated construction, by the upper dowel 25. One side of the spring 40 bears against the front of the socket in which the spring is housed, and the other side of the spring thrusts against a lug 42 extending downwardly from the under side of the slide 30.

The slide 30 is held against upward displacement by the undercut sides of the guideway 26, and this guideway also holds the slide 30 against transverse displacement. Movement of the slide 30 along the length of the guideway 26 is limited by the lug 42 which strikes against the abutment provided by the rearward wall of the socket when the slide 30 reaches the full line position shown in Figure 1, and which pushes the spring 40 against the forward wall of the spring socket when the slide 30 is moved into the dotted line position shown in Figure 1.

The end of the slide 30 which moves back and forth across the discharge opening 17 preferably has a sharpened edge for cutting off the paste 31 without requiring the spring 40 to be excessively heavy. There is no end wall at the rearward end of the guide 26 and it is, therefore, impossible for the closing of the slide 30 to be prevented by an accumulation of the paste between the end of the slide and the end wall of the groove or guideway in which the slide moves back and forth.

The preferred embodiment of the invention has been illustrated and described, but changes and modifications can be made, and some features of the invention can be used alone or in different combinations, without departing from the invention as defined in the claims.

What is claimed is:

1. A collapsible tube cap having upper and lower ends and comprising two sections with recesses in confronting faces shaped and positioned to form a threaded socket for the end of the collapsible tube at the lower end of the cap, a channel in the surface at the upper end of the cap with undercut side walls and serving as a guideway, each of said walls being on a different section of the cap, said channel being open at both ends and also having a discharge opening through its bottom, a slide movable back and forth along the guideway for covering and uncovering the discharge opening, an upwardly extending flange at one end of the slide at a distance from the other end of the slide equal to the height of a tooth brush with which the cap is intended to be used and by which the slide can be moved with the tooth brush, said slide having an unobstructed top surface on the side of the flange nearest to the discharge opening so that a side of the tooth brush can be laid across the slide and moved toward the flange end of the slide, a downwardly extending lug under the slide, a socket in the cap below the slide in position to receive the downwardly extending lug of the slide, said lug being of a size to cooperate with the ends of the socket and thereby limit the stroke of the slide in both directions, a spring in the socket urging the slide towards closed position, said spring having a loop intermediate its ends, and fastening means securing sections of the cap together, one of said fastening means extending through the socket and through the loop of the spring for maintaining the spring at a fixed location within the socket.

2. An automatic cap for a collapsible tube, said cap including two sections that fit together to form a threaded opening on one end of the cap for receiving the end of the tube and to form a channel at the other end of the cap to serve as

a guideway, said channel having side walls one of which is on each of the respective sections, and both of which sides are undercut, a slide movable along the guideway and across an outlet which opens through the bottom of the channel and which communicates with the threaded opening of the cap through a passage in said cap, which passage is substantially longer than the maximum width of the outlet, said slide having side edges that extend into the undercut portions of the guideway and having a top surface that is substantially flush with the top edges of the guideway, and a flange extending upwardly from the slide toward one end thereof for a substantial distance to prevent the tooth brush from jumping over the flange when pressed against the flange to move the slide into position to uncover the discharge passage, the channel formed by the assembly of said sections being open at both ends.

3. A collapsible tube cap having a threaded opening in its underside for screwing on the neck of the tube and a guideway in its upper side, extending transversely across the cap and open at both ends, and having a discharge opening extending longitudinally of the cap intermediate the ends of the guideway, a slide at least as short as the guideway and confined throughout its length between the sides of the guideway, the slide being movable along the guideway for covering and uncovering the discharge opening, a flange extending upward from the top surface of the slide near one end of the slide that is remote from the discharge opening when the slide is in position to uncover the opening, said slide having an unobstructed top surface on the side of the flange nearest to the discharge opening so that a side of the tooth brush can be laid across the slide at a slope that brings the upper ends of the bristles on one side of the brush adjacent to the top surface of the slide, and the brush can be moved into contact with the flange to shift the slide into position to uncover the opening, a socket under the slide, and spring means in the socket urging the slide toward the position in which it covers the opening, an abutment in the socket limiting movement of the slide to a position in which one end of the slide just clears the discharge opening, the flange extending above said top surface on the side of the flange toward said discharge opening far enough to provide a ledge for the tooth brush and to prevent the sloping tooth brush from jumping over the flange when pressed against the flange to move the slide into position to uncover the discharge opening, and the length of the slide from the flange to the end of the slide nearest to the discharge opening being equal to the height of the tooth brush with which the cap is intended to be used.

4. A collapsible tube cap having a channel in a top face in the cap with a discharge opening in the bottom surface of the channel, said channel being open at both ends and having undercut side walls and serving as a guideway, a slide having longitudinal edges that fit in the undercut side walls of the channel, said slide being movable lengthwise along the channel into different positions to cover and uncover the discharge opening, a flange extending upward from the top surface of the slide near the end of the slide remote from the discharge opening, said slide having an unobstructed top surface on that side of the flange which is nearest to the discharge opening so that a side of a tooth brush can be laid across the slide and moved along the slide into contact

with the flange to shift the slide into position to uncover the opening, said flange extending upwardly from the slide and having a straight surface above the top of the guideway on the side of the flange which is toward the discharge opening and for a distance sufficient to prevent a tooth brush from jumping over the flange when pressed against the flange to move the slide into position to uncover the discharge opening, said cap also having a recess in the bottom of the channel under the slide, said recess having abutment surfaces at its opposite ends, a lug on the bottom of the slide projecting downward into the recess and located in position on the slide to be stopped by the end faces of the recess to limit movement of 15 the slide in both directions lengthwise of the channel.
